UNITED STATES PATENT OFFICE.

JOHN G. KREMERS, OF MILWAUKEE, WISCONSIN.

PROCESS FOR REFINING SUGAR.

1,107,172.

Specification of Letters Patent. Patented Aug. 11, 1914.

No Drawing.

Application filed July 30, 1913. Serial No. 781,940.

To all whom it may concern:

Be it known that I, JOHN G. KREMERS, a citizen of the United States, residing at Milwaukee, in the county of Milwaukee and State of Wisconsin, have invented a certain new and useful Improvement in Processes for Refining Sugar, of which the following is a full, clear, concise, and exact description.

This invention relates to processes of 10 clarifying and refining impure sugar solutions, more particularly sugar solutions in which more or less glucose and combined potash are both present. The refining of such solutions has heretofore been attended 15 with considerable difficulty owing to the fact that by the methods heretofore practised the potash, at one stage or another of the refining process, has been present in the form of an alkaline reacting compound and 20 has therefore reacted destructively on whatever glucose might be present to give dark colored products whose elimination from the juice and resultant crystallized sugar has been extremely difficult and practically impossible in many instances. It is for this 25 reason, among others, that great difficulty has been experienced heretofore in attempting to produce refined sugar direct from raw cane juices.

One of the main objects of the present invention is to obviate the difficulties heretofore experienced in this respect and to render feasible direct production of refined sugar from raw cane juices coming directly 35 from the mill. The broad principles of the invention are also applicable to solutions of sugar derived from other sources, such as partially refined cane sugar, masse-cuite or fillmass, cane syrups, cane molasses, etc.

According to ordinary methods of refining sugar juices, a raw sugar solution is first defecated by treating it with lime and by heating. After removal of the scum, the excess of lime is then removed by passing in 40 carbon dioxide gas, this carbonatation usually taking place in several stages. After separation of precipitated matter, the juice is then concentrated to obtain crystallized sugar. Operating in this way, whatever 45 potash there was originally present in the sugar solution is present after the carbonatation either as potassium carbonate or bicarbonate, or it is combined with one or more organic acids present in raw sugar solutions. 50 These organic acids are for the most part very feeble acids, and consequently their

potassium salts are alkaline in reaction. As a consequence, the potash present as carbonate or as an organic salt reacts with any glucose present if the temperature of the 60 sugar solution be carried above a relatively low point, resulting in the decomposition of the glucose and consequent darkening of the solution.

According to the process of the present invention, the above difficulties are avoided by carefully controlling and regulating the conditions under which the lime remaining in the sugar solution after defecation is removed, and by insuring the conversion of 70 any potash present in the sugar solution into a stable compound having a neutral or non-alkaline reaction and consequently having no power to decompose glucose in the manner described. In this way the injurious effects 75 of potash in alkaline reacting condition are entirely avoided, the potash being for all practical purposes removed from the field of action.

In a typical example of the present process, a raw sugar solution of about 22° Baumé contained in a suitable receptacle is treated with lime either in the form of milk of lime or as powdered lime in the approximate proportion of three parts of lime (CaO) to 80 one hundred parts of crystallized sugar by weight. The amount of lime added naturally depends upon the condition of the particular sugar solution in question, but sufficient must be added to insure proper filtration and decoloration. The liming operation is best carried on at a temperature not exceeding about 45° C. After defecation, the limed solution is then treated with carbon dioxide gas which is passed into the solution until a test sample shows approximate neutrality to phenolphthalein or to an equivalent indicator of the phenolphthalein type. At this point the lime has been substantially 90 all precipitated as calcium carbonate, while 100 the potash is probably present in combination with the weak organic acids of the sugar juices. A small amount of lime may also still remain in solution in more or less complex combination. These weak organic acid potash salts, while not alkaline toward phenolphthalein, are alkaline to litmus; and the reaction of the carbonated solution at this point, although substantially neutral to phenolphthalein, is therefore still alkaline to 105 litmus. At this point, the solution is best transferred to another treating tank where 110

sulfur dioxid is run in until the solution is substantially neutral to litmus or to an equivalent indicator of the litmus type. In fact, in some cases, particularly in treating 5 raw cane juices coming directly from the mill, it is distinctly advantageous to go more or less beyond the point of neutrality to litmus and to render the solution slightly acid in reaction. In this treatment with 10 sulfur dioxid, the organic acid salts of potash are decomposed with the formation of potassium sulfite and the corresponding free organic acids. The presence of these free organic acids in the solution seems to protect the sugar from the harmful effects 15 which might otherwise be experienced from any excess of sulfur dioxid in the solution. Any lime still remaining after carbonatation is precipitated as calcium sulfite by this 20 treatment.

Instead of using sulfur dioxid or sulfurous acid as above described, phosphoric acid may be employed for rendering the solution neutral or somewhat acid to litmus 25 after carbonatation has been carried to the point of neutrality to phenolphthalein. In this case the potash is finally obtained in the form of potassium phosphate. Any residual lime is, of course, precipitated as phosphate 30 when phosphoric acid is used. Both potassium sulfite and potassium phosphate are stable salts of neutral reaction and without decomposing effect on glucose at the temperatures employed in concentrating purified sugar solutions. 35

The steps above described are best carried out at comparatively low temperatures and ordinarily it is advantageous not to exceed about 45° C.

40 After the treatment above described, the sugar solution may be freed from precipitated matter in any suitable way as, for example, by heating to say 90° C. or higher and then filtering through filter presses or 45 other convenient filtering means. The potash being now present in a form non-reactive toward glucose, the temperature of the solution may be raised to any reasonable extent without fear of darkening its color 50 by destruction of glucose. Consequently the temperatures employed during the filtering operation may be as high as is desirable or convenient to insure rapidity in the filtering operation. The filtered solution 55 may be further treated and purified as desired, or it may be immediately concentrated and the sugar crystallized out in the ordinary manner.

What I claim is:

60 1. The process of treating impure sugar solutions which comprises defecating such a solution by means of lime, carbonating until the solution is substantially neutral to an indicator of the phenolphthalein type, 65 and then treating the carbonated solution

with an acid capable of forming a stable neutral salt with potash.

2. The process of treating impure sugar solutions which comprises defecating such a solution by means of lime, carbonating 70 until the solution is substantially neutral to an indicator of the phenolphthalein type, and then treating the carbonated solution with sulfurous acid.

3. The process of treating impure sugar 75 solutions which comprises defecating such a solution by means of lime, carbonating until the solution is substantially neutral to an indicator of the phenolphthalein type, 80 and then treating the carbonated solution with sulfurous acid in quantity at least sufficient to render the solution substantially neutral toward an indicator of the litmus type.

4. The process of treating impure sugar 85 solutions which comprises defecating such a solution with lime, carbonating to a point at which the solution is approximately neutral to phenolphthalein, and treating with sulfur dioxid until the solution is substantially 90 non-alkaline to litmus.

5. The process of treating impure sugar solutions which comprises defecating such a solution with lime, carbonating to a point at which the solution is approximately neutral to phenolphthalein, and treating with sulfur dioxid until the solution is somewhat 95 acid to litmus.

6. The process of treating impure sugar solutions which comprises defecating such 100 a solution with lime, carbonating to a point at which the solution is approximately neutral to phenolphthalein, treating with sulfur dioxid until the solution is substantially non-alkaline to litmus, the solution being 105 maintained at a relatively low temperature during these steps, and thereafter heating and filtering the treated solution.

7. In the purification of impure sugar 110 juices the process which comprises carbonating lime-defecated juice to approximate neutrality toward phenolphthalein, and then treating the carbonated solution with an acid capable of forming a stable neutral salt with potash. 115

8. In the purification of impure sugar then treating the carbonated solution with 120 sulfurous acid at least until the solution is substantially neutral to litmus.

9. In the purification of impure sugar juices the process which comprises carbonating lime-defecated juice to approximate 125 neutrality toward phenolphthalein, and then treating the carbonated solution with sulfurous acid at least until the solution is substantially neutral to litmus, the solution being maintained at a temperature not 130

higher than about 45° C. during these steps.

10. In the purification of impure sugar juices the process which comprises carbonating lime-defecated juice to approximate neutrality toward phenolphthalein, and then treating the carbonated solution with sulfurous acid at least until the solution is substantially neutral to litmus, the solution 10 being maintained at a temperature not

higher than about 45° C. during these steps, thereafter heating, filtering and concentrating the treated solution.

In witness whereof, I hereunto subscribe my name this 21st day of July, A. D. 1913. 15

JOHN G. KREMERS.
